A. M. MACE.

Vapor Lamp.

No. 20,649.

Patented June 22, 1858.

UNITED STATES PATENT OFFICE.

A. M. MACE, OF SPRINGFIELD, MASSACHUSETTS.

VAPOR-LAMP.

Specification forming part of Letters Patent No. 20,649, dated June 22, 1858; Reissued September 4, 1860, No. 1,034.

To all whom it may concern:

Be it known that I, ALONZO M. MACE, of the city of Springfield, in the county of Hampden and State of Massachusetts, have 5 invented a new and useful Improvement in Hydrocarbon - Vapor Burners; and I do hereby declare the following to be a full, clear, and exact description of the construction and operation of the same, reference 10 being had to the annexed drawings, making part of this specification.

The nature of my invention consists in providing heating and vaporizing tubes or retorts used in vaporizing hydro-carbon 15 liquids by the heat of burners supplied with vapor generated within the tube or retort, with a heat retaining cover or cap so connected to the retort as to retain or reflect the heat upon or around the surface opposite 20 the flame.

It also consists in such an arrangement of the parts herein after mentioned as to produce the perfect vaporization of the hydrocarbon fluid, and a high degree of 25 illumination, as hereinafter stated, the pipe conducting the fluid between the valve and burner being made continuous and so bent as to pass upward from a point below the burner, thence over the flame, receiving the 30 heat at its intermediate part, thus forming the siphon shaped conduit whereby a glass globe and its sustaining fixture may readily be attached.

To construct my invention make a reservoir (N) of tin or other suitable material to 35 contain any desirable quantity of carbonaceous liquid and placed in the upper part of a building to be lighted or at any convenient elevation above the burner so that the 40 liquid is forced through the apparatus by hydrostatic pressure. Coal gas fixtures in common use may be used to convey the liquid to the generator and burner. The valve (C') may be connected in the usual place of 45 the common gas burner, and is made like the common globe valve, except that its spindle (D) and seat (E) in the diaphragm is made nearly straight to nicely regulate 50 the flow of the liquid to the generator. To the valve (C') connect the conducting pipe (G) and to this attach the vaporizing tube or retort (B-A) so bent at its upper part as to bring it over the flame of the burner

(K). The retort or tube may be charged or packed with fibrous or light material as 55 shown at (P-P) to equalize the flow of the fluid through the retort. To the upper part of the retort at (A) connect a cover or cap (H) which may be made of iron, brass, or other material, and may be made concave upon its under surface or in any other form whereby the heat of the flame is retained or reflected upon the upper surface or around the vaporizing tube, the object being to heat the tube upon the side opposite 60 the flame. The vapor generated within the retort or tube (B-A) is conducted by a pipe (J) to the burner (K).

The fluid is conducted by pipes (C) and (G) to the vaporizing tube and is charged 70 into the tube and through the packing by hydrostatic pressure from the fountain (N), the vaporizing tube or retort may be made of sheet brass or iron formed into a tube and bent at its upper part so that a portion 75 of its surface is over the flame exposed to a high degree of heat.

I do not claim now the use of the heat retaining cap connected with a retort of a particular construction, as such a patent was 80 granted to me in April 22nd 1856,—but generally it may be applied to any form of chamber or retort producing the same results. Neither do I claim the elevated reservoir except in connection with parts here- 85 mentioned. Neither do I now claim expanding the vaporizing tube into a chamber, as I intend applying for a separate patent for that device.

What I claim as my invention and desire 90 to secure by Letters Patent, is—

1. Combining the cap or heat retainer (H) with vaporizing tubes or retorts constructed substantially as described when so arranged over the plane as to operate in the 95 manner set forth.

2. I also claim the combination of the heat retainer (H) and vaporizing tube connected substantially as described; with the elevated reservoir, the whole arranged and 100 operating with respect to the valve (C') and burner (K) as set forth.

ALONZO M. MACE.
